UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

PULLING-OVER MACHINE.

1,090,220.

Specification of Letters Patent. Patented Mar. 17, 1914.

Application filed October 12, 1906. Serial No. 338,635.

To all whom it may concern:

Be it known that I, RONALD F. McFEELY, a citizen of the United States, residing at Beverly, in the county of Essex and Commonwealth of Massachusetts, have invented certain Improvements in Pulling-Over Machines, of which the following description, in connection with the accompanying drawings, is a specification, like reference characters on the drawings indicating like parts in the several figures.

This invention relates to machines for pulling boot and shoe uppers over lasts.

The machine in which the invention is herein shown as embodied comprises, among other mechanisms, means for resting a last at the heel, means for gripping the upper and pulling it over the last, means for resting the bottom or sole of the last and sinking the last into the pulled upper, means for clamping the upper when the grippers release it and for pressing the edge portion of the upper over the last bottom in a position to be secured, and means for inserting 25 tacks to secure the upper.

The improvements contemplated by this invention have for their objects to cause the different mechanisms to perform their several functions better and to coöperate more 30 perfectly in the operation of the machine as a whole.

One feature of the invention consists in providing an adjustable heel rest. It is found in practice that in lasts of different 35 styles the heel portions vary in shape and in the inclination of the extreme rear end with relation to the fore part. Inasmuch as the fore part of the shoe is the portion most affected in the pulling-over operation 40 it is desirable that the heel rest be so positioned that it may firmly sustain different styles of lasts with their fore parts in approximately the same angular position with 45 relation to the planes in which the sole rest and the grippers are located. As herein shown, the heel rest is movably connected with its supporting means for adjustment about an axis extending transversely of the last and approximately parallel with the 50 last bottom. Advantageously the heel rest may be positioned to form an acute angle with the plane of the sole rest. In such position it is most effective in upholding the heel end of the last against the tendency 55 which exists to a greater or less extent for

the shoe to fulcrum on the sole rest, its toe end rising and its heel end descending in response to the pull of the grippers upwardly on the fore part of the shoe.

The sole rest is arranged to be engaged by the innersole on the bottom of the last for determining the initial position of the shoe with relation to the plane in which the grippers are located and in which they will grip the upper when they are closed. A cam is provided in operative relation to an arm of the sole rest carrier for moving the rest to sink the last into the upper after the grippers have grasped the edges of the upper, a spring serving to return the sole rest to normal position after the operation of the cam.

In accordance with another feature of this invention, novel means is provided for adjustably determining, positively, the normal position of the sole rest, and also the extent to which the last shall be moved for sinking it into the upper. As herein shown this means comprises an unyielding adjustable stop arranged upon the arm of the sole rest carrier in position to engage a rigid portion of the machine when the rest is in its normal raised position. By this construction the position in which the shoe shall be presented with relation to the plane of the grippers may be accurately predetermined by the sole rest and there is no liability that pressure of the shoe against the sole rest before the grippers are closed will cause the upper to be introduced too far into the grippers. The extent of the sinking movement of the last can also be accurately determined and reliably varied according to the requirements of different shoes.

In accordance with a very important feature of this invention, means is provided for simultaneously increasing or diminishing the force with which the several grippers are actuated to pull the upper over the last so that the strain upon the upper will be properly adapted to the class of shoes being pulled over by the machine, or to the quality of the leather of a particular shoe. In the machine herein shown, the movement of the operating bars for closing and uplifting the grippers is yieldingly effected through springs interposed between the levers to which the operating bars are connected, and the cams by which the levers are actuated.

The initial tensions of the springs are determined by the devices which confine the springs in position. It is desirable however, to adjust the tension of these springs during the operation of the machine, so as to increase or diminish their power and, hence, the pulling strain applied thereby to the grippers. It is also sometimes desirable to change the pulling strain upon the upper after the uplift of the grippers has been automatically effected by the cam and connected parts above described. Under that feature of the invention which is being described, means is provided by which the tension of the updraw springs can be readily adjusted so as to increase or diminish their force, and such adjustments may be effected while the machine is at rest and the upper is under pulling strain, or during its operation, the adjustments referred to being manually effected, and preferably simultaneously for the several gripper mechanisms.

In the illustrated embodiment of the invention, adjusting devices, such as wedges are interposed between the updraw levers and the springs through which the updrawn movement of the levers is effected. The wedges are preferably connected to a single manually operable member by which they may be adjusted to vary the tension of the springs, a lever, which is located in convenient position for engagement by the operator's hand, being the form of this member selected herein for illustration. The wedges may be adjusted while the machine is running, or they may be adjusted while the machine is at rest, after the grippers have pulled the upper and before they release it, to diminish the pulling strain upon the upper, or to increase it on such classes of work as will permit the advancement of the wedges while the upper is under the pulling strain. It will of course be understood that the straining of the upper is effected by a relative movement of the grippers and the last and that the same results would be produced by moving either the grippers or the last.

In accordance with another feature of the invention novel means is provided which is adapted to clamp the upper before the grippers release it and to wipe the upper over the last bottom and press it firmly into position to be secured after the grippers have released it. This means, which for convenience will be herein referred to as the "presser", is shown as comprising a device having a vertically inclined end face and a lower face substantially parallel with the last bottom. The inclined face is adapted to engage and clamp the upper against the edge of the last before the grippers release it and by its pressure against the shoe to wedge the last downwardly after the grippers release the upper. In this downward

movement the last is forced into position to permit the presser to slide over the last bottom for laying the upper into position to be secured to the innersole. In the machine shown as embodying the invention two similar pressers are arranged to coöperate with the two side grippers located upon opposite sides of the shoe. Preferably movable last supports are employed for sustaining the last against the wedging action of the pressers and as shown the pressers and last supports are mounted upon carriers movable laterally toward the last and each presser is operatively connected with its co-operating last support so that as it wedges the last downwardly, causing the support to yield, said presser will be advanced inwardly over the last, or will have its advance movement accelerated, by the displacement of the support. Preferably also the presser will be mounted to have a positioning movement with relation to its carrier to enable it to adapt itself to the plane of the portion of the bottom face of the last over which the upper stock is to be pressed. The presser is also preferably arranged for movement to adapt its position to the contour of the portion of the side face of the last adjacent to it. These two movements of the presser enable it to position itself automatically in accordance with the contour of the edge of the last so that it may clamp the upper securely thereagainst throughout the width of the presser or its extent in the direction of the edge of the last. Preferably means is provided for holding the presser in a normal central position and returning it to such position after the operation of the machine upon each shoe.

In the operation of the illustrated machine the pressers at opposite sides of the last are advanced into clamping engagement with the upper while the grippers are still pulling the upper and thereby holding the last against vertical downward displacement by the inclined front faces of the pressers. The carriers for the pressers and last supports are yieldingly actuated toward the last and when the grippers have released the upper the inclined front faces of the pressers wedge the last downwardly, causing the last supports to yield until the last is depressed far enough for the pressers to slide inwardly over the last bottom. It is desirable that the pressers and last supports be forced against the last with considerable pressure before the grippers release the upper, so as to insure that the upper will be securely clamped by the pressers against backward movement. Yielding means is, therefore, provided through which said carriers are actuated and in practice it is preferable that the tension of this yielding means be approximately uniform for large and for

small shoes. To obtain this result provision is made in accordance with one feature of this invention for adjusting the carriers with relation to their actuating means. As herein shown each carrier comprises an arm formed in two parts which are adjustably connected whereby the pressers at opposite sides of the last may be initially positioned with relation to their actuating means and nearer to or farther from each other according to the sizes of shoes to be operated upon by the machine.

These and other features of the invention, including certain details of construction and combinations of parts, will be fully explained in the following description and pointed out in the annexed claims.

In the drawings, which show a preferred embodiment of this invention, Figure 1 is a side elevation of a pulling-over machine. Fig. 2 is a central vertical section of a portion of the machine in the plane of the driving shaft. Fig. 3 is a perspective view of the heel rest illustrating the adjustable connection between the heel rest and its support. Fig. 4 is a side elevation, partly in section, of the sole rest and of a portion of a shoe after the upper has been pulled and the last sunk into the pulled upper. Figs. 2 and 4 illustrate the mechanism for effecting and controlling the swinging movements of the sole rest. Fig. 5 is a view in plan and section of the arms which carry the clamping devices and shoe supports and the mechanism for actuating said arms. The figure shows in dotted lines the provision for adjusting said arms with relation to their actuating mechanism to adapt the parts carried by them to shoes varying widely in size. Figs. 6 and 7 are side elevations of the devices carried by one of the arms shown in Fig. 5 for clamping the upper and pressing it into position and for supporting the shoe. Fig. 7 shows a relative position of the pressing device and shoe while said device is operative for clamping the upper against the edge of the last before the grippers release the upper. The arrows indicate the direction of relative movement of the several parts as they come into the position shown in Fig. 6. Fig. 8 is a detail view showing a modified construction of the presser designed to avoid displacement of innersoles by pressure upon their edges. Figs. 9 and 10 are, respectively, plan and front views of the presser and show in full and dotted lines different positions which the presser is enabled to assume, by reason of its swivel connections with its holder, in adapting itself to the shape of different lasts. Figs. 11 and 12 are perspective views, respectively, of the presser and one of the members of its holder and illustrate the swivel connections which permit the movements of the presser for

conforming to the shape of a last engaged by it. Fig. 13 is a view illustrating the relation of the swiveled grippers and the swiveled presser in acting upon upper stock at the toe tip seam of the shoe. Fig. 14 is a perspective view of a modification. Fig. 15 is a section on line 21—21 of Fig. 14.

The head B of the machine is supported upon a column and provided with bearings for a driving shaft D driven by a pulley 986 and having connection with the several driving mechanisms of the machine which, except as hereinafter pointed out, will preferably be constructed and arranged substantially as shown and described in detail in United States Letters Patent No. 1,029,387, granted June 11, 1912 on my application filed March 28, 1903. The heel rest 4, which is pivotally connected to a support which comprises the horizontally swinging hangers 56, is arranged for adjustment with relation to said support. As herein shown, the connection between the heel rest and the support comprises a bar 2 having a pivotal connection with the lower ends of each of the hangers 56 and provided with ears 6 having pivotal connection at 8 with the heel rest. One of the ears 6, shown in Fig. 3, has a lateral extension and is provided with a slot concentric with the pivot bolt 8. The heel rest receives a clamping screw 10 which passes through the slot in the plate 6 and is adapted to bind the heel rest against said plate in different adjusted positions within the range of the slot. The heel rest may thus be made to have such an acute angular relation to the sole rest that it will extend downwardly and forwardly under the heel end of the shoe and prevent the shoe from fulcruming on the sole rest in response to the pull of the grippers, particularly the toe grippers, which tends to rock the toe end of the shoe upwardly and the heel end downwardly. By reason of this arrangement the heel rest may be adjusted about an axis extending through the bolts 8, and which is substantially parallel with the bottom of the last, and said rest may be secured in adjusted position by the bolt 10. The hangers 56 are arranged to rock forwardly and backwardly about a pivotal connection 54 with a block 50, which itself is mounted to swing laterally. These connections provide for the horizontal swinging movement of the heel rest and also for a slight forward and backward movement. A spring 58 holds the hangers and heel rest normally swung forwardly as shown in the drawings, where they are out of touch with a fixed part 64 which is located directly behind the hangers. Said fixed part and the hangers are provided with interlocking portions by means of which the heel rest is locked against horizontal swinging movement after it has adjusted itself

laterally to the position of the shoe being supported and has been pressed backwardly against the tension of springs 58 to bring said interlocking portions into engagement.

5 The sole rest, which comprises arms for engaging the fore part of the last bottom at a plurality of points and holding the last against upward movement during the pulling-over operation, is mounted in a carrier 10 120 pivoted upon a transverse shaft 301. The carrier has an upwardly extending arm 12 provided with a roller stud adapted to engage a cam 378 upon the front end of the main shaft D, by which the carrier is rocked 15 about the shaft 301 to actuate the sole rest for sinking the last into the upper while the upper is held by the grippers. The carrier is rocked in the reverse direction by a spring α , see Fig. 2. It is desirable to vary 20 the extent to which the sole rest is rocked for sinking the last into the upper and for this purpose the arm 12 is extended vertically above the cam 378 and is provided with an adjustable stop 14 adapted to engage the frame B of the machine when the cam occupies a position in which a low portion of its acting face is presented to the arm 12. By adjusting the stop 14 the arm 12 may be held in different positions with 25 relation to the cam 378 and will receive from said cam movements of correspondingly differing extents for rocking the sole rest to sink the last. In presenting a shoe to the machine it is held upwardly by the 30 operator against the sole rest while the edges of the upper are introduced into the grippers, and when the machine is started the grippers close and are uplifted for pulling the upper about the last. It is desirable 35 that the sole rest present a firm abutment 40 against which the last shall be presented always in the same position with relation to the grippers and which shall hold the last firmly against the pull of the grippers. To 45 this end the stop 14 is made unyielding so that it will rigidly hold the sole rest against displacement by pressure of the last against said rest.

The gripper mechanisms are herein 50 shown as arranged for engaging the upper at the opposite sides of the fore part of the shoe and also at the toe of the shoe. These gripper mechanisms may embody the construction disclosed in United States Letters Patent No. 959,874, granted May 31, 1910, on an application filed as a division 55 of this application, or they may embody any other construction suitable for use with the present improvements.

60 The movement of the operating bars 68 for closing and uplifting the grippers is yieldingly effected in the machine herein shown through springs 150, 170 interposed between the levers 153, 154, to which the operating bars are connected, and the cams by which 65 the levers are actuated. The initial tensions of the springs 150, 170 are determined by the devices 140, 141, which confine the springs in position. It is desirable, however, to adjust the tension of these springs, 70 during the operation of the machine, in accordance with the class of shoes being pulled over or with the quality of the leather of a particular shoe. To this end a notched wedge block 30 is interposed between the 75 rear end of each of the gripper levers 153, 154 and the springs 150, 170, a collar 32 being interposed between each spring and the cooperating wedge block and formed to fit the notches in said block. The wedge blocks 80 are each connected by means of links 34 with the upper arm of a lever 35 fulcrumed at 152 and extending into position to be conveniently engaged by the operator while the machine is running, whereby the wedge blocks 85 may be shifted forwardly or backwardly to increase or diminish the tension of the springs. Preferably the notches or seats are located to correspond to the maximum and minimum tension which it is desirable to 90 give the springs and there may be also notches whose locations correspond to one or more intermediate tensions. Preferably also each wedge block, cooperating with each of the gripper springs, is connected to the same 95 operating lever 35, whereby the tension of all the springs may be adjusted simultaneously. This construction also enables the operator to shift the several wedges for increasing or decreasing the tension of the 100 springs 150, 170, through which the upper is held under strain after the grippers have pulled it in their automatic movements. It will be understood that there are three 105 gripper mechanisms, one for the toe and one for each of the opposite sides, although the grippers mechanism and its operating lever and spring located on the right hand side of the machine are hidden in the side elevation of the machine shown in Fig. 1.

The devices for clamping and holding the upper when the grippers release it and pressing it into position to be secured to the innersole, and the devices for supporting the last after the grippers release it and during 115 the tack-driving operation, are carried by arms 29 α , 22 α , shown in Figs. 1 and 5. The presser comprises a member 40 which is angular or L-shaped in end elevation and has on its horizontal arm a vertically inclined 120 front face 42 and a plane lower face 44. The front face of the depending arm of the presser is shaped to engage the side of the shoe. The rear face of said depending arm is provided with a semi-cylindrical shoulder 125 45 having a peripheral rib 46. The shoulder is formed to fit into a recess in the side face of a block 48 having a groove 49 shaped to fit and interlock with the rib on the shoulder 45. This connection between the presser and 130

the block permits the presser to move about an axis extending transversely of the last and substantially parallel with the last bottom so that the presser may adapt itself to 5 differences in the thickness of different portions of the upper engaged by it and to the longitudinal curvature or spring of the portion of the last bottom itself. The extent of this movement is limited by a rib formed on 10 the block and having provided oppositely inclined stop faces 47 adapted to be engaged by faces 50, 52 on the depending member of the presser. The presser is held in the block by a pin 53 which extends from the block 15 and axially through the semi-cylindrical shoulder of the presser. The pin is held in position by a key or bolt 55. The block 48 to which the presser is directly connected as above described is itself connected by 20 a curved tongue and groove to the slide 59, whereby said block may have movement about a vertical axis extending transversely of the last and located adjacent to the front face of the depending member 25 of the presser. This movement enables the presser to adapt itself to the contour of the side of the last, as illustrated in full and dotted lines in Fig. 9. Means is provided for holding the presser and block 30 48 in a normal central position and returning them to this position after each operation. This means comprises a spring-pressed plunger 57 carried by the slide 59 and having a beveled end received in a recess in the rear side of the block 48, as shown 35 in Fig. 9. The recess has inclined faces co-operating with the end faces of the plunger to return and hold the block in a central position. The slide 59 is movable in a trans- 40 verse horizontal guideway in the front end of its carrying arm, as shown in Figs. 6 and 9, and is provided on its lower side with rack teeth adapted to engage a pinion 60 mounted in the arm and itself engaging with rack 45 teeth on a slide 62. The slide 62 carries a last support 65 and is movable in the arm 22^x in a guideway which extends downwardly and outwardly from the region of the presser. These parts are so arranged 50 that when the carrying arm is moved toward the last the presser will, by its inclined face 42, engage the edge of the shoe, as shown in Fig. 7, while the last support engages the side and lower face of the shoe. These en- 55 gagements take place while the grippers are still holding the upper, and after the upper has become securely clamped between the inclined face 42 of the presser and the last the grippers are released and the pressure of 60 said inclined face against the last wedges the last downwardly against the support 65. The last moves in this direction until the presser can slide over the last bottom and force the upper material into contact with the innersole in position to be secured.

The directions of relative movement of the last, presser, and support are indicated by arrows in Fig. 7 and the final position of these parts is shown in Fig. 6. A spring 66 resists downward movement of the last support 65 and returns that support and the presser to their normal position when said parts are moved from engagement with the shoe. It is sometimes found that the relation of the innersole to the edge of the last is such that the innersole is liable to be forced back from the edge of the last by pressure applied to the side of the shoe opposite the innersole. To avoid danger of the innersole being displaced inwardly on 70 the last bottom by the action of the depending member of the presser said presser may be formed as shown in Figs. 6 and 14 with a recess 68 in the upper portion of said depending member. The horizontal member 75 of the presser is preferably notched, as shown at 70, to permit the securing tacks to be driven through it into the portion of upper held against the innersole by the presser.

In Figs. 14 and 15 is shown a modified construction in which the member 40 is formed in two parts, 41, 41, relatively movable vertically. To this end the parts 41 are provided with cylindrical stems 43 which slide in guideways in the front face of a member 45^a which corresponds in function with the block 48 of Figs. 9, 12 and 13. The stems 43 are connected by an equalizing lever 47^a that compels them to move together, but in reverse directions. This construction permits the members 41 to adapt their position approximately to the contour of inclination of the portion of the shoe bottom engaged by them.

The carrying arms 20^x, 22^x, which are formed as angle levers pivoted on studs 16^x, 18^x depending from the machine frame, are actuated for moving the pressers and last supports toward and from the last by a yielding connection between the rear, inwardly projecting portions of said arms and a cam N³² on the driving shaft D. The rack bars N²⁴, springs N⁴⁰, equalizer NN⁷ connected by a stud N²⁷ with the slide N³⁵ which carries the stud N³⁶ in position to be engaged by the cam N³³ composing this connection, form no part of this invention and are, therefore, not herein more fully described. It is desirable to adjust the pressers and last supports with relation to the last into different initial positions—as, for example, to enable them to act with approximate uniformity upon lasts of different sizes or to increase the pressure of said devices upon the work for different kinds of shoes. As herein shown the arms 20^x, 22^x are each formed in two parts a and b, see Figs. 1 and 5. The parts a are carried by the inwardly projecting portions of the arms and extend 100 105 110 115 120 125 130

forwardly beneath the parts *b* on which are carried the presser and last support. The parts *b* are provided with depending bolts *c* which extend through slots in the parts *a* whereby said parts *a* and *b* may be secured in adjusted relation.

In the use of the machine the heel rest may, by loosening a clamping bolt 10, be adjusted in accordance with the shape of the 10 style of last to be used, and to prevent downward displacement of the heel end of the shoe, and the sole rest may be adjusted by positioning the stop 14 to cause the cam 378 to give the desired amount of movement to 15 said sole rest for sinking the last into the upper. The arms 20^x, 22^x for the pressers and last supports are adjusted by relatively moving their parts *a* and *b*, and the springs 150, 170, through which the grippers are 20 operated, are set at the desired tension by manipulating the lever 35 to position the wedge blocks 30. These adjustments having been made, if necessary, the shoe is presented to the machine by holding it against 25 the sole rest and the heel rest with the edge portion of the upper between the jaws of the grippers. When the machine is started, the grippers close and grip the upper and are then uplifted to pull the upper, where- 30 upon the machine comes to rest to give opportunity for the operator to inspect the shoe and if necessary to manipulate the lever 35 for moving the wedges 30 to increase or decrease the pull of the grippers upon the upper. 35 When the machine is restarted the arms 20^x, 22^x are actuated for moving the last supports inwardly toward the last and positioning the pressers to clamp the upper against the edge of the last. As the pressers come 40 into engagement with the last they turn about their vertical and horizontal axes to adapt themselves to the contour of the portions of the edge of the last engaged by them. When the pressers have clamped the 45 upper the grippers are automatically released and the last is forced slightly downwardly by the inclined front faces of the pressers to permit the pressers to move over the last bottom for pressing the upper into 50 position to be secured. The release of the grippers is in practice effected by the engagement of the inwardly moving tack-driving mechanisms with the latches 204. The tack drivers are then operated to force 55 the tacks from the tack holder 600 into the upper and innersole, the tacks passing through the notches 70 in the pressers so that they are inserted into the portion of the stock held downwardly on the innersole 60 by the presser. After the tacks have been driven the several operating mechanisms of the machine are restored to their starting positions, the withdrawal of the pressers and last supports freeing the pulled-over shoe.

Having explained the nature of the invention and fully described so much of a machine embodying the invention as is necessary for a complete understanding of the invention, I claim as new and desire to secure by Letters Patent of the United States:

1. In a machine of the class described, a heel rest supported for free lateral swinging movement and also adjustable about an axis which extends transversely of the last to be supported and is located adjacent to the end face of said last substantially midway of the height of the rest, and means for securing the rest in different angular positions.
2. In a pulling-over machine, means for gripping an upper to pull it over a last, a rest for the bottom of the last, and a support for the heel of the last constructed and arranged to be adjusted about an axis located between its upper and lower edges into positions of different inclination to the first mentioned rest.
3. In a machine for pulling an upper over a last, means for gripping the upper at a plurality of points in the length of the last, and a support for the heel of the last constructed and arranged to be adjusted about an axis located between its upper and lower edges into positions of different inclination to the plane in which said gripping means are located.
4. In a pulling-over machine, the combination with a laterally swinging heel rest, a support therefor and a relatively fixed part provided with members arranged to be interlocked with the support for holding the rest against swinging movement, of a connection between the heel rest and the support arranged to permit the rest to be shifted substantially perpendicular to its lateral movement.
5. In a machine of the class described, the combination with a movably supported sole rest, and means for actuating it to sink a last into an upper, of means for returning the sole rest to normal position, and adjustable means for positively limiting the return movement of the sole rest and rendering the rest unyielding to the pressure of the shoe against it.
6. In a machine of the class described, the combination with a pivotally supported sole rest, a cam, an arm on the sole rest having a part in position to be engaged by the cam for moving the rest angularly, yielding means for actuating the arm toward the cam, and unyielding means on said arm above the cam for engaging a fixed part of the machine to determine the angular shoe receiving position to which the rest is returned.
7. In a pulling-over machine, means for gripping an upper at a plurality of points

- in the length of the shoe, a movable rest against which the shoe may be presented for the engagement of the grippers with the upper, means for rocking said rest with 5 relation to the plane in which the gripping means are located, means for returning the rest to normal position, and an adjustable unyielding stop for determining the position to which the rest may be moved by said 10 returning spring.
8. In a pulling-over machine, the combination with a plurality of grippers for engaging an upper at different points in its length, a heel rest and a sole rest for supporting the shoe in operative relation to the grippers, a support for the heel rest, and connections between the heel rest and support arranged to permit shifting of the heel rest about an axis extending transversely of 15 the shoe into different shoe receiving positions, of means for actuating the sole rest angularly with relation to the heel rest to sink the last into the upper, means for returning the sole rest to normal position, and 20 unyielding, adjustable means for determining the position to which the sole rest is returned and fixing its angular shoe receiving position with relation to the heel rest.
9. In a machine for working an upper over a last, the combination with a plurality of yieldingly actuated grippers mechanisms, of means under control of the operator and adapted for adjustment into different positions for simultaneously varying 30 the force with which the several grippers mechanisms shall be actuated.
10. In a machine for working an upper over a last, the combination with a plurality of grippers and actuating mechanisms including springs through which said grippers are lifted to pull the upper, and means for causing a rest in the machine's operation while the upper is held under tension, of notched wedges for controlling the tension 40 of said springs, and means under control of the operator for adjusting said wedges while the upper is held under tension.
11. In a machine for working an upper over a last, the combination with a plurality 50 of grippers for engaging the upper at different points, and means for automatically actuating the grippers to pull the upper, of means under control of the operator and adapted for adjustment into different positions for thereafter changing simultaneously 55 the pulling strain with which the upper is held by the several grippers.
12. In a machine for working an upper over a last, the combination with a rest for 60 the last, grippers for engaging the upper at a plurality of points, automatic means for relatively moving the grippers and last to strain the upper, and manually controlled means which is adjustable to different posi- 65 tions for thereafter simultaneously moving the several grippers and the last relatively in the line of strain to change the tension of the pulled upper.
13. In a machine of the class described, the combination with a presser, a support 70 therefor, and means for actuating the presser, of connections between the presser and its support constructed and arranged to permit the presser to turn about an axis extending transversely of the last in substantially 75 the plane of the last bottom, and yielding means for returning the presser to a normal position when it has been turned.
14. In a machine of the class described, the combination with a presser, a support 80 therefor, and means for actuating the presser, of a connection between the presser and its support, comprising an arc-shaped undercut guiding groove in one of said parts, and a guiding rib on the other part 85 shaped to fit in said groove.
15. In a machine of the class described, the combination with a presser, a support therefor, and means for actuating the presser, of a connection between the presser 90 and its support, comprising an arc-shaped undercut guiding groove in one of said parts, a guiding rib on the other part shaped to fit in said groove, a locking pin for securing the parts in assembled relation, and 95 means for fastening the pin in place.
16. In a machine of the class described, the combination with a presser having a face for engaging the side of the shoe and a face for engaging the bottom of the shoe, of a 100 support for the presser and connection between the support and presser constructed and arranged to permit the presser to turn about a substantially vertical axis parallel with the side of the last and about a horizontal 105 axis extending transversely of the last substantially parallel with the last bottom.
17. In a pulling-over machine, the combination with grippers for pulling an upper over a last, and means movable in approximately 110 the plane of the last bottom into position for holding the upper over the last after the pulling operations, of a support upon which said holding means is arranged to turn about an axis extending transversely 115 of the last to adapt itself to the inclination of the surface of the work, and means to actuate said holding means toward and from the last.
18. In a pulling-over machine, the combination with means for supporting a last, and means for pulling an upper over the last, of an unyielding presser having a vertically inclined front face, and means for actuating said presser laterally toward the last to 120 clamp the upper between said inclined face and the edge of the last, said presser being mounted for movement about an axis ex- 125

tending transversely of the last to permit it to adapt its position to the contour of the shoe.

19. In a pulling-over machine, the combination with means for supporting a last, and means for pulling an upper over the last, of an unyielding presser having a vertically inclined front face for engaging the shoe at the edge of the last, a depressible support for the last, means for actuating said presser and support laterally toward the last, and a connection between the support and presser for accelerating the movement of the presser when the support is depressed by engagement with the last.

20. In a pulling-over machine, the combination with means for supporting a last, and means for pulling an upper over the last, of an unyielding presser having a vertically inclined front face for engaging the shoe at the edge of the last, a last support mounted to move downwardly and outwardly with relation to the last, a carrier for said parts movable laterally toward the last, and connections between the support and presser whereby the inclined face of the presser may wedge the last downwardly and the support will advance the presser inwardly over the last.

21. In a machine of the class described, a pressing device having a member for passing over the shoe bottom to lay the upper down upon the innersole, and a member for engaging the side of the shoe to force the upper against the side of the last, said latter member being formed with a recess opposite the edge of the sole.

22. In a machine of the class described, the combination with grippers for pulling an upper about a last, a presser having a face for engaging the last, a depressible support for the last, means for releasing the grippers from the upper, and means for actuating the presser to clamp the upper between the edge of the last and said face before the grippers are released and thereafter to depress the last and slide over the upper to wipe it over the last bottom while maintaining a constant angular relation to the shoe.

23. In a machine of the class described, the combination with grippers for pulling an upper about a last, of a presser arranged to maintain a constant angular relation with the plane of the last bottom, a depressible support for the last, means for releasing the grippers from the upper, and means for actuating the presser to clamp the upper against the edge of the last before the grippers are released and thereafter to depress the last and wipe the upper over the last bottom.

24. In a machine of the class described, the combination with grippers for pulling an upper about a last, of a presser, means

for releasing the grippers from the upper, and means for actuating the presser to clamp the upper against the edge of the last before the grippers are released and thereafter to depress the last and slide over the upper to wipe it over the last bottom while maintaining the same angular relation to the last bottom throughout the last depressing and upper wiping operations.

25. In a machine for working an upper over a last the combination with pressers for engaging opposite sides of a shoe, carriers for said pressers formed as bell crank levers, means for actuating the carriers, and means whereby the two arms of the levers may be adjusted relatively in substantially the plane of the shoe bottom.

26. In a machine for working an upper over a last the combination with pressers for engaging opposite sides of a shoe, carriers for said pressers, means for actuating said two carriers together, and means for adjusting the carriers separately with relation to the actuating means in substantially the plane of the shoe bottom.

27. In a machine of the class described, a presser comprising two members relatively movable toward and from the surface to be acted upon, a block upon which the members are mounted and a connection between the pressers and block comprising interlocking portions carried by the two parts and an equalizing lever carried by the block and operatively connected with each member of the presser.

28. In a machine for working an upper over a last, the combination with a plurality of yieldingly actuated grippers mechanisms arranged to seize and hold an upper under tension, of means under the control of the operator for simultaneously increasing or diminishing the force with which the upper is held by the several grippers mechanisms.

29. In a machine for working an upper over a last, the combination with a plurality of grippers for engaging the upper at different points, and means for automatically actuating the grippers to pull the upper, of means under the control of the operator for thereafter simultaneously increasing or diminishing the pulling strain with which the upper is held by the several grippers.

30. In a machine for working an upper over a last, the combination of a rest for the last, grippers for engaging the upper at a plurality of points, automatic means for relatively moving the grippers and last to strain the upper, and manually controlled means for thereafter simultaneously effecting relative movement of the several grippers and the last in the line of strain to increase or to diminish the tension of the pulled upper.

31. A pulling-over machine having, in combination, a plurality of pairs of grippers

- and automatic mechanism for causing the grippers to yieldingly pull simultaneously and to hold under tension the upper at opposite sides of the last, and a single hand lever arranged at the side of the machine for engagement and control by the operator during the operation of the automatic mechanism for governing the yielding tension applied to the grippers by said mechanism.
- 10 32. In a machine for pulling an upper over a last, a sole rest, means for gripping the upper at a plurality of points in the length of the last, and a support for the heel of the last constructed and arranged to be positioned at an acute angle to the plane of the sole rest to prevent downward displacement of the heel end of the last.
- 15 33. In a machine of the class described, means for pulling an upper over a last, a sole rest, and a rest shaped to embrace the heel end of the last and arranged to be positioned in an acute angular relation to the plane of the sole rest and to extend downwardly and forwardly under the heel end of the last and thereby prevent downward displacement of said heel end in response to the upward pull on the fore part of the upper.
- 20 34. In a machine of the class described, means for pulling an upper over a last, a sole rest, and a heel rest having wings constructed to embrace an inverted last, and arranged to be positioned in a downwardly and forwardly inclined relation to the sole rest to resist downward movement of the heel end of the last in response to the upward pull on the fore part of the upper.
- 25 35. In a machine of the class described, means for pulling an upper, a sole rest, and a rest shaped to embrace the heel end of a last and inclined forwardly and downwardly relative to said sole rest.
- 30 36. In a machine of the class described, means for pulling an upper over a last, an abutment for engaging the sole of the shoe to resist the pulling strain, and a rest shaped to embrace the heel end of the last and inclined forwardly and downwardly relative to the shoe sole.
- 35 In testimony whereof I have signed my name to this specification in the presence of two subscribing witnesses.

RONALD F. McFEELY.

Witnesses:

WILLIAM B. PIERCE,
JAMES R. HODDER.

Correction in Letters Patent No. 1,090,220.

It is hereby certified that in Letters Patent No. 1,090,220, granted March 17, 1914, upon the application of Ronald F. McFeely, of Beverly, Massachusetts, for an improvement in "Pulling-Over Machines," an error appears in the printed specification requiring correction as follows: Page 8, line 61, strike out the words "wipe the upper" and insert the words *slide over the upper to wipe it*; and that the said Letters Patent should be read with this correction therein that the same may conform to the record of the case in the Patent Office.

Signed and sealed this 11th day of August, A. D., 1914.

[SEAL.]

J. T. NEWTON,
Acting Commissioner of Patents.

- and automatic mechanism for causing the grippers to yieldingly pull simultaneously and to hold under tension the upper at opposite sides of the last, and a single hand lever arranged at the side of the machine for engagement and control by the operator during the operation of the automatic mechanism for governing the yielding tension applied to the grippers by said mechanism.
- 10 32. In a machine for pulling an upper over a last, a sole rest, means for gripping the upper at a plurality of points in the length of the last, and a support for the heel of the last constructed and arranged to be positioned at an acute angle to the plane of the sole rest to prevent downward displacement of the heel end of the last.
- 15 33.
